(57) **CLAIM**

The ornamental design for a wall mount drying rack, as shown and described.

DESCRIPTION

FIG. 1 is a front perspective view of a wall mount drying rack, showing my new design in an open state;

FIG. 2 is a rear perspective view thereof;

FIG. 3 is a top perspective view thereof;

FIG. 4 is a bottom perspective view thereof;

FIG. 5 is a front view thereof;

FIG. 6 is a rear view thereof;

FIG. 7 is a right-side view thereof;

FIG. 8 is a left-side view thereof;

FIG. 9 is a top view thereof;

FIG. 10 is a front view of its folded state;

FIG. 11 is front perspective view of its folded state; and,

FIG. 12 is a top view of its folded state.

1 Claim, 12 Drawing Sheets
